UNITED STATES PATENT OFFICE.

WILLIAM C. WOLF, OF FORT WAYNE, INDIANA.

DESIGN FOR A FURNACE-CASING.

54,159.

Specification for Design.

Patented Nov. 4, 1919.

Application filed April 12, 1918. Serial No. 228,271. Term of patent 14 years.

To all whom it may concern:

Be it known that I, WILLIAM C. WOLF, a citizen of the United States, residing at Fort Wayne, in the county of Allen and State of Indiana, have invented a new, original, and ornamental Design for a Furnace-Casing, of which the following is a specification, reference being had to the accompanying drawing, forming part thereof.

The figure is a front elevation showing my new design.

I claim—

The ornamental design for a furnace casing, as shown.

WILLIAM C. WOLF.

Witnesses:

MATILDA METTLER,
SOPHIA HEINE.
